UNITED STATES PATENT OFFICE.

CHARLES E. BROMAN, OF GRAND RAPIDS, MICHIGAN, ASSIGNOR, BY MESNE ASSIGNMENTS, TO ADD-INDEX CORPORATION, A CORPORATION OF DELAWARE.

CALCULATING MACHINE.

Application filed November 4, 1920. Serial No. 421,748.

My invention relates to the means whereby the crank handle, or other power element, is connected with the calculating mechanism to actuate the latter after the same has been preliminarily set, and the object of the invention is to provide such a connection as will be simple in construction and in operation for the purpose of preventing any undue strain from being imposed upon the calculating mechanism. According to my invention, if the calculating mechanism does not yield to a normal amount of force, a portion of my connecting means will move with the handle and leave the calculating mechanism uninjured. And my invention consists in the parts and combinations thereof, for such purposes, hereinafter set forth and claimed.

With such objects in view as well as other advantages which may be incident to the use of the improvements, the invention consists in the parts and combinations thereof hereinafter set forth and claimed, with the understanding that the several necessary elements constituting the same may be varied in proportions and arrangement without departing from the nature and scope of the invention.

In order to make the invention more clearly understood there are shown in the accompanying drawings means for carrying the same into practical effect, without limiting the improvements, in their useful applications, to the particular constructions which, for the purpose of explanation, have been made the subject of illustration. In said drawings—

Fig. 1 is a side elevation of the actuating and power-controlling mechanism of a calculating machine, showing the embodiment of my invention in its preferred form, the parts being in normal position before the actuation of the same.

Fig. 2 is a plan view of the same.

Fig. 3 is a side view of the same in a position in which the power element or crank handle has received its extreme forward movement, and the calculating mechanism has not moved, and the connecting mechanism has assumed its position to permit the movement of the handle and to allow the calculating mechanism to remain stationary.

Fig. 3' is a plan view of the same.

Figs. 4 to 9 inclusive are detail views of various elements of my connecting means,

shown separately and in side elevation, and hereinafter more particularly described.

Fig. 10 is a side elevation of the mechanism in a position after its full forward actuating movement, in which the calculating mechanism has also been normally moved to perform its functions.

Fig. 11 is a plan view of the same.

Fig. 12 is a side view of certain of the parts, to more clearly illustrate them apart from the others.

Referring to the drawings, 1 is a portion of the frame of an adding machine, and 2 the main power shaft mounted in suitable bearings (not shown) on the frame to turn forward and backward therein in a known manner for the operation of the machine. 3 is a crank handle having a hub 4 which fits on the shaft 2, but may turn relative to the shaft. The shaft is formed with a groove 5 into which fits a spring-pressed ball or other keeper enclosed in a housing 6 fixed on the handle, this arrangement leaving the handle free for turning on the shaft but holding it from endwise displacement. For said handle may be substituted a motor or other driving appliance, in a known manner, for actuating the shaft.

7 is the full stroke sector fixed on the shaft 2, with which sector cooperate in a known manner pawl devices shown at 8 to compel the full stroke to be made after it has begun. 9 is a dash pot or governor fixed to the machine frame and having its rotary or other piston or movable element connected by a link 10 with the sector to retard the return or backward movement of the mechanism. 11 is a stud fixed on the sector with which is connected an arm 12 mounted loosely on the shaft 2. This connection is preferably effected by a pawl 13 which is pivoted at 14 to the arm 12 and bears against the stud 11. 15 is a spring which is connected at one end with the hub of the arm 12 and at its other end with the end of the pawl and causes the pawl to take up any looseness between the arm and the stud 11 and gives a constant bearing of the arm on the stud through the medium of the pawl. Consequently when the arm 12 moves forward the sector and shaft 2 make a corresponding partial rotation.

16 is a link of triangular shape, or having three pivotal points, which is pivoted at one of said points 17 to the arm 12, said pivot

being a projecting stud. Another of said pivotal points 18 is connected by a link 19 with the main retracting spring 20, the other end of said spring being attached at 21 to the dash pot or other fixed part of the machine frame. The third pivotal point 22 of the link 16 is connected by a link 23 with a finger 24. This finger has a hub-portion 25 which fits loosely around the shaft 2 and is formed with radial apertures 26 (Fig. 7) in which fit lugs 27 (Fig. 2) formed on the hub of the handle. Consequently the handle and finger turn together, either with the shaft 2, or relative thereto when the sector 15 resists turning. As shown in Fig. 1 the handle is in its rearmost or normal position of rest, the turning of the handle and finger being arrested by the pivot stud 17 against which the hook or end 28 of the finger is engaged. Various means may be used to effect this stoppage without departure from my invention. In this position all of the parts, including the link system, are stabilized under the stress of the main retracting spring 20, because turning in any direction would increase the stress in the spring. The sector is provided with an independent means to arrest its backward movement consisting of the stud 29 fixed in the machine frame, in order that the sector and shaft may come to normal position accurately, and not disorganize the adding mechanism with which the shaft is connected.

The stabilization of the parts at rest as above described results from their combination and the arrangement of their various centers of motion or pivots, as shown, but it will be understood that my invention extends to various equivalent combinations.

Starting from the position shown in Fig. 1, if the handle be pulled forward, and the sector be not held by any catch in the adding mechanism or otherwise, the finger 24 will accompany the handle and pull upward by link 23 on a line near the main pivot 17 of the triangular link, so that it is easier for the pivot 17 and the arm 12 to follow the finger and handle than for the triangular link 16 to turn on said pivot, such turning being resisted by the spring which tends to turn the link 16 down anti-clockwise rather than up. In this movement the stud 17 remains in contact with the finger, and the arm 12 carries forward with it the stud 55 11, sector 7 and shaft 2. (Fig. 10.)

But if the sector be held stationary, by any accident, obstruction, or imperfection, the finger 24 will leave the stud 17 and by means of the link 23 will turn the link 16 upward and backward (to the right in Fig. 1), the link system will or can open out to the position shown in Fig. 3, and the handle will perform its ineffective movement without injury to the adding mechanism.

65 When the handle is released or moved back-

ward the spring 20 will restore the parts to the position shown in Fig. 1. The handle need not be turned to the full extent shown in Fig. 3, which shows the full capacity of the mechanism in that respect.

In order to properly control the link 19 in this movement and keep it between the pivots 17 and 22 I arrange a stop for it, which is conveniently a lateral lug 30 formed on the link 16 and engaging with the rear edge of the link 19 (Figs. 2 and 3). When the sector moves with the handle this stop will disengage from the link.

I have thus what may be best described as a folding system of links which is extensible under the pull of the handle, in case of obstruction to the operation of the adding mechanism, and is contractible under the pull of the main spring 20, the links which have such folding function being in this instance the links 16 and 23.

31, 32 are stops on the lower part of the finger 24 adapted to engage respectively with the front or rear side of a stud 33 which is fixed to the machine frame, whereby the forward and backward movements of the handle are limited.

In the ordinary operation of the machine, when the sector turns, the spring 20 will not be extended so much as is shown in Fig. 3.

It will be apparent that the mechanism which connects the handle with the shaft is such that the same degree of movement of the handle gives to the main spring two different extensions—a lesser extension when the shaft turns with the handle and greater extension when the handle turns and the shaft remains stationary; and from this it results that the mechanism will operate in the manner which requires the less extension of the spring unless some obstruction necessitates the greater extension.

It may also be observed that the elements to be connected are the handle and the shaft. I use the sector as a convenient agency in the connection but the connection could be made without the use of the sector for that purpose.

What is claimed is—

1. In a calculating machine, a shaft-driving flexible and yielding connection, comprising in combination, a shaft, a member fixed on said shaft, another member carried by said shaft and independently rotatable on the same and contacting with said first member, a power-transmitting member loosely mounted on said shaft, a spring, and intermediate connecting parts between said members and said spring, the arrangement of said intermediate connecting parts requiring greater power to expand the flexible connection and spring when at normal than after such expansion has commenced.

2. In a calculating machine, a shaft-driv-

ing flexible and yielding connection, comprising in combination, a shaft, a member fixed on said shaft, another member carried by said shaft and independently rotatable on the same and contacting with said first member, a power-transmitting member loosely mounted on said shaft, a spring, and intermediate connecting parts between said members and said spring, the arrangement of said intermediate connecting parts requiring greater power to expand the flexible connection and spring when at normal than after such expansion has commenced, and means for holding said spring in a substantially straight line between its anchorage and said shaft.

3. In a calculating machine, a shaft-driving flexible and yielding connection, comprising in combination, a shaft, a member fixed to said shaft, another member carried by said shaft and independently rotatable thereon and contacting with said first member, a power transmitting member loosely mounted on said shaft, a spring, and intermediate connecting parts between said members and said spring, the arrangement of said intermediate connecting parts being such that when resistance of the first named member to the second member is less than predetermined the parts move together in normal relation to one another, and when said resistance is greater than predetermined the parts move out of their normal relation to one another; said parts and spring requiring greater power from the power-transmitting member to be started than to be changed in their relative position after they have been started.

4. In a calculating machine, a shaft-driving flexible and yielding connection, comprising in combination, a shaft, a member fixed to said shaft, another member carried by said shaft and independently rotatable thereon and contacting with said first member, a power-transmitting member loosely mounted on said shaft, a spring, and intermediate connecting parts between the power-transmitting member and said first member comprising a link pivoted to said second member and a second link connecting the latter with said power-transmitting member, a third link pivoted to the first link and connected with the spring, and a stop carried by the second member against which stop said power-transmitting member is held by said spring.

5. In a calculating machine, a shaft-driving flexible and yielding connection, comprising in combination, a shaft, a member fixed to said shaft, another member carried by said shaft and independently rotatable thereon and contacting with said first member, a power transmitting member loosely mounted on said shaft, a spring, and intermediate connecting parts between the power

transmitting member and said first member comprising a link pivoted to said second member and a second link connecting the latter with said power transmitting member, a third link pivoted to the first named link and connected with the spring, and a stop carried by the second member against which stop said power transmitting member is held by said spring, the position relative to said first link of the link which connects the first link to the power transmitting member being almost in a straight line with the pivot which connects the first link and said second member, thereby requiring more power to initially swing the first link on its pivot than is required after said first link has commenced to swing.

6. In a calculating machine, a shaft-driving flexible and yielding connection, comprising in combination, a shaft 2, a sector 7 fixed on said shaft, an arm 12 loosely mounted on said shaft, a finger and links connecting the shaft with said arm, a spring 20, a link 19 connecting said spring with said first mentioned link, a stop 17 carried by said arm against which said finger is held by said spring, a pawl 13 carried by said arm, and a stud on said sector with which said pawl engages.

7. In a calculating machine, a shaft-driving flexible and yielding connection, comprising in combination, a shaft 2, a sector 7 fixed on said shaft, an arm 12 loosely mounted on said shaft, a link 16 pivoted to said arm, a finger 24 loosely mounted on said shaft and connected with said link, a second link 23 performing said connection, a spring 20, a link 19 connecting said spring with said link 16, a stop 17 carried by said arm against which said finger is held by said spring, a pawl 13 carried by said arm, a stud on said sector with which said pawl engages, and a lug 30 to engage said link 19 and thereby cause the spring to remain in a substantially straight line between its anchorage and said shaft when the parts of the flexible connections are positioned relative to one another.

8. In a calculating machine, a shaft-driving flexible and yielding connection, comprising in combination a shaft for operating the calculating mechanism, a driving member fixed to said shaft, a driving member loose on said shaft, means whereby said loose member may actuate said fixed member, a power element loose on said shaft, a spring extensible by the actuating movement of said element, and connecting parts arranged intermediate the power element and the spring and intermediate the power element and the shaft and acting to decrease the length of the spring during the forward actuating movement of said power element.

9. In a calculating machine, a shaft-driving flexible and yielding connection, com-

prising in combination a shaft for operating the calculating mechanism, a driving member fixed to said shaft, a driving member loose on said shaft, means including links pivoted to fold past each other and also to be extended whereby said loose member may actuate said fixed member, and a spring connected with said links and extensible by the actuating movement of said shaft, said links causing said spring during the turning of the shaft constantly to exert its pull in substantially the line of the shaft.

10. In a calculating machine the combination of the driving shaft of said machine, a handle loose thereon, an arm loose on said shaft, means whereby said arm can actuate the shaft, a pair of links pivoted together and one of which has a pivotal connection whereby it can pull on said handle and the other of said links being pivoted to said loose arm, and a spring having a pivotal connection with the other of said links.

In testimony whereof I affix my signature.

CHARLES E. BROMAN.
